UNITED STATES PATENT OFFICE.

GEORGE L. KNOWLTON, OF PHILADELPHIA, PENNSYLVANIA, ASSIGNOR OF ONE-HALF
TO ELWOOD F. WALTER, OF PHILADELPHIA, PENNSYLVANIA.

DEVICE FOR PLAYING PUSSY OR BALL.

Application filed October 10, 1922. Serial No. 593,517.

To all whom it may concern:

Be it known that I, GEORGE L. KNOWLTON, a citizen of the United States, residing in the city and county of Philadelphia, 5 State of Pennsylvania, have invented a new and useful Device for Playing Pussy or Ball, of which the following is a specification.

My invention consists of a device for 10 playing the game of "pussy or ball" or for ball-throwing, the same embodying a lever one limb of which is provided with a receiver for a ball, and the other limb is adapted to be struck by stick or bat, 15 whereby the ball is ejected upwardly when it is to be hit by said stick or bat and so thrown to an extent under the rules of the game.

It consists also of a stop member which 20 is adapted to be engaged by the lever so that the ball is caused to leave the lever by greater inertia and so impelled upwardly or more forcibly and to a greater height.

The invention is satisfactorily illustrated 25 in the accompanying drawing, but the important instrumentalities thereof may be varied, and so it is to be understood that the invention is not limited to the specific details shown and described, as long as they are within the spirit or scope of the claims.

Figure 1 represents a partial side elevation 30 and partial vertical section of a device for playing pussy or kitty embodying my invention.

Figure 2 represents a top or plan view 35 thereof.

Figure 3 represents a partial side elevation 40 and partial vertical section of a modification of a portion of the device.

Similar numerals of reference indicate 45 corresponding parts in the figures.

Referring to the drawings,

1 designates the base of the device consisting 50 of a block or piece of wood or other material which is to be placed on the ground or a floor so as to support the device in operative position.

2 designates a swinging lever which is placed above the base and is mounted thereon by the bolt or pivot 3 which is passed 55 freely through a transversely extending opening 4 in the lever whose bearings are on the ears 5 which rise from the base 1 and are firmly secured thereto, thus providing 60 the axis of the lever, said bolt being

retained in position by its head 6 and the 55 nut 7 or other suitable means.

On the upper side of the limb 8 of the lever is secured the cup or socket 9 which is adapted to hold a displaceable member 10 shown as a ball in dotted lines, said cup 60 thus weighting said limb whereby in its normal position it is lowered on the base while the other limb 8^x of the lever is held elevated from the base whereby when said limb is struck by the stick or bat of the 65 game, it is depressed and so the limb 8 is forcibly elevated when the ball 10 is thrown upwardly out of the cup and it is to be hit on its flight by the stick or bat and so directed elsewhere according to the rules of 70 the game.

In order to impart a more forcible motion to the ball when the limb 8^x is depressed and the ball is about to leave the cup, I secure to the base the vertically extending 75 rod 11 which is passed upwardly and freely through the vertical slot 12 in the limb 8 of the lever. The rod 11 freely occupies the slot 12 in the lever 2, and thus the limb 8^x is guided true especially in its ascent 80 and is prevented from being twisted laterally whereby the dart is caused to be impelled true from the holder.

On the upper end of said rod which is screw-threaded is the nut 13 forming a head 85 which overhangs the walls of said slot and occupies a position above the upper part of limb 8. When the limb 8^x is depressed the limb 8 suddenly strikes said nut and is stopped against the same and so causes the ball to leave the cup by greater inertia 90 whereby the ball receives an impetus which throws it more quickly and to a greater extent from the cup. The nut may be raised or lowered on the rod and so adjusted to 95 permit the limb 8 to be elevated to a greater or less extent according to requirements.

In Figure 3, I show the rod having on its upper end the head 14 and its threaded end below, said end engaging with the nut 15 which is secured to the base 1. By this provision the head 14 receives the impact of the lever 2 and it may be adjusted in height by rotating the rod in the nut 15, the operation being the same as in the previous case.

It is evident that when the ball leaves the socket the lever returns to its normal

position ready to have the ball re-seated in the socket and the limb 8^x struck as before.

If desired, when the device is played as "pussy" what is known as the "kitty" thereof may be substituted for the ball.

Having thus described my invention what I claim as new and desire to secure by Letters Patent, is:—

1. In a game of the character stated, a base, an ear rising therefrom, a swinging lever, an axial connection for said lever with said ear, an upwardly projecting holder to receive a displaceable member, said holder being secured to a limb of said lever, said limb having therein a vertically extending slot, and a guide rod rising from said base and passing freely through said slot.

2. In a game of the character stated, a base, an ear rising therefrom, a swinging lever, an axial connection for said lever with said ear, an upwardly projecting holder to receive a displaceable member, said holder being secured to a limb of said lever, said limb having therein a vertically extending slot, and a guide rod rising from said base and passing freely through said slot, the upper portion of said rod having thereon a head whose diameter is greater than that of said slot, so as to overhang the wall of the latter.

3. In a game of the character stated, a base, an ear rising therefrom, a swinging

lever, an axial connection for said lever with said ear, an upwardly projecting holder, a displaceable member, said holder being secured to a limb of said lever, said limb having therein a vertically extending slot, and a guide rod rising from said base and passing freely through said slot, the upper portion of said rod having thereon a head whose diameter is greater than that of said slot, so as to overhang the wall of the latter, said head being vertically adjustable in height.

4. In a game of the character stated, a lever, a base on which the lever is pivotally mounted, a holder to support a displaceable member arranged upon a limb to said lever, said lever being adapted to be normally lowered toward said base, the opposite limb being normally elevated above said base, a rod provided with a head, which rod is attached to the base and passes upwardly and freely through a slotted part of the first mentioned limb, said head overhanging said slot, said limb carrying said holder being adapted when raised to strike and impel said displaceable member to a great length, said head being adapted to be adjusted in height.

GEORGE L. KNOWLTON.
